UNITED STATES PATENT OFFICE.

ELLIS C. HEALY, OF EAST ORANGE, NEW JERSEY, AND RUSSELL S. BROWN, OF BROOKLYN, NEW YORK, ASSIGNEES, BY MESNE ASSIGNMENTS, TO DETEX WATCH-CLOCK CORPORATION, OF NEW YORK, N. Y., A CORPORATION OF DELAWARE.

SUPERVISING DEVICE FOR VALVES.

Application filed October 14, 1920. Serial No. 416,877.

To all whom it may concern:

Be it known that we, ELLIS C. HEALY and RUSSELL S. BROWN, both citizens of the United States of America, residing at, respectively, East Orange, in the county of Essex and State of New Jersey, and Brooklyn, in the county of Kings and State of New York, have invented certain new and useful Improvements in Supervisory 5 Devices for Valves, of which the following is a full, clear, and exact description.

The invention which constitutes the subject-matter of this application has to do with mechanism adapted to be connected to a 10 valve and for controlling the access to a recording key. That is to say, when the valve is in its normal position access may be had to a recording key but if the valve is not in its normal position the key is rendered in 15 accessible. As these valves (or "stations") are equipped with a key a time imprint may be made on a record dial of a watchman's clock which indicates the time at which the station was visited by the watchman. So 20 long as these imprints are made at the required intervals, as shown by the record dial, it is a sure indication that the valves at these particular times were in normal position.

But if the imprint of a certain station is 25 omitted from the record dial it would be an equally sure indication that the key at that station was inaccessible and therefore that valve was not in normal condition. Of course, if it is a part of the watchman's duty 30 to move the valve from its abnormal to its normal position he could then make the imprint. In any event, the device will have 35 served its purpose.

Referring to the drawings:

40 Figure 1 is a partly sectional view of the upper portion of an indicator post or yard valve equipped with supervisory mechanism.

Figure 2 is a section, through the receptacle containing supervisory mechanism, 45 taken at right angles to that of Fig. 1.

Fig. 3 is an elevation illustrating a complete valve and its equipment.

Figs. 4 and 5 are fragmentary detail views 50 showing different positions of certain of the parts.

The supervisory mechanism herein illustrated, described and claimed is particularly designed to be employed in connection with an indicator post or yard valve which con-

trols a sprinkler system located in an adjacent building. The indicator post is composed of two sections 10 and 11 which telescope with each other and are relatively adjustable. The section 10 is fixed upon and supported by the valve 12 which is to be controlled by the device. Superimposed upon the upper section 11 is a cap 13 suitably secured to the section 11. There is provided a wrench member 17 which is rotatably mounted in the cap 13 but constrained 55 against axial movement. The lower end of the wrench member 17 is provided with a rectangular socket (as is usual in valves of this type) which engages with the upper end portion of the valve stem, which we have 60 designated by the reference numeral 20. The lower end of this valve stem 20 is provided with a socket member 21 which engages with the upper end of a suitably shaped member 22 constituting a part of the 65 valve 12.

All of the mechanism described above is of conventional form and no claim is made thereto except as it forms or constitutes a 70 part of the combination with the mechanism 75 described hereinafter.

The stem 20, which is square in cross-section, has mounted thereon a sprocket wheel 80 operatively connected by means of a chain 31, which passes through suitable 85 openings in casing 11 and housing 32, to a sprocket wheel 33. The wheel 33 is secured to a screw 34 rotatably mounted in the housing 32 but constrained against axial movement, said housing being bolted or otherwise 90 suitably secured to the casing 11. The screw 34 is provided with a nut 35 secured to a slide member 36 at or adjacent the lower end of the latter. This slide member 36 is mounted for vertical reciprocatory movement, only, between guide pins 37 carried by a bracket 38 secured to the housing 32. A shaft 39, journaled in brackets 40 secured to the housing 32, has secured thereto a cam 41 and an arm 42. The cam 41 engages 100 with and is operable by the slide 36 in the longitudinal movement of the latter. The arm 42 has secured thereto, by means of a chain 43, a watchman's key or other manually operable record-producing device 44. 105 It will be noted that the housing 32 is provided with a detachable septum or dust cap 45 which divides the housing into two com-

parts, in one of which the major portion of the mechanism is located and in the other of which the arm 42, chain 43 and key 44 are located. The front of the housing 32 is provided with a lock-controlled door, hinged at 47 to said housing, and the septum 45 may be removed through the opening controlled by this door and access had to the housing-contained mechanism by anyone 10 having the proper key to open said door. The principal function of the door 46 may therefore be said to be to permit inspection or repair of the mechanism by authorized persons but to prevent tampering with the 15 same by unauthorized persons.

The door 46 is provided at its lower portion with an opening through which the watchman can obtain access to the key 44 to produce a record, when the arm 42 occupies 20 the position shown in full lines in Fig. 2. This opening is preferably normally closed by a lock-controlled closure or door 48 hinged at 49 on the larger door 46. The housing 32 is thus effectively sealed against 25 unauthorized tampering. The watchman would be provided with a key to the lock of the door 48 and may therefore obtain access to the key (provided it is accessible through the openings in the door 46) and any 30 unauthorized person may obtain access through the door 46 for inspection or repair.

As applied to a sprinkler system the form of invention disclosed above is designed to operate substantially as follows: If the 35 valve 12 is in normal position or condition, i. e., fully open, the parts occupy the position illustrated in Figs. 1, 2 and 4 and the watchman may obtain access to the key 44 and produce a record therewith on the blank 40 in his watchman's clock or other recorder. If, however, the valve 12 is partially or fully closed the arm 42 occupies the position shown in dotted lines in Fig. 2 and the key is in such a position that the watchman can no longer 45 obtain access to the key, through the opening controlled by the door 48, to produce a record at that station. There would therefore necessarily be a blank space upon the watchman's record card and such a blank 50 space would indicate either that the watchman had not visited that station at the time corresponding to the blank space (in which event he would be reprimanded) or that the valve 12 was not fully open. As stated 55 above, if the valve 12 is not fully open the watchman cannot obtain access to the key 44. The reason for this may be set forth more fully as follows.

In order to close the valve 12 it is necessary 60 to rotate the stem 20. Assuming that the parts are in the normal position, rotation of said stem 20 to close the valve causes rotation of sprocket wheel 30, wheel 32 and consequently screw 34. This rotation of the 65 screw 34 causes the nut 35 to travel up-

wardly and as the slide 36 is secured to this nut, the slide will also move upwardly. As soon as the slide moves from its normal position (see Fig. 4) it causes rotation of the cam 41 and consequently arm 42 until the 70 cam assumes the position illustrated in Fig. 5 and the arm the position illustrated in dotted lines in Fig. 2. The parts are preferably so designed that a few (say two) turns of the stem 20 towards valve-closing 75 position will cause the cam 41 and arm 42 to assume the last described position in which the key 44 is inaccessible. Bearing in mind that a comparatively large number of turns of the stem 20 are required to close the valve 80 12 completely, it will be appreciated that the key 44 will be inaccessible to the watchman when the valve is only slightly closed. Continued rotation of the stem 20 toward valve-closing position simply locks the cam 41 (see 85 Fig. 5) and arm 42 (see dotted line position of arm 42 in Fig. 2) in the position in which the key is inaccessible. Obviously if the stem 20 is rotated in the opposite direction 90 reverse operation takes place and the key 44 will again be rendered accessible to the watchman. But it should be noted that such access to the key 44 will not be re-established until the valve is fully opened.

Many advantages inherent in our invention 95 will be apparent in view of the foregoing description. We wish to direct especial attention to the fact that the invention may readily be applied to all types of yard and other valves comprising rotary stems or operating members. Furthermore 100 all of the key-controlling parts, including the chain 31, are sealed against unauthorized tampering. The importance of these and other features will be clearly understood by 105 those skilled in the art.

In accordance with the provisions of the patent statutes, we have herein described the principle of operation of our invention, together with the apparatus which we now 110 consider to represent the best embodiments thereof, but we desire to have it understood that the apparatus disclosed is only illustrative and that the invention can be carried out by other means. Also while it is designed to use the various features and elements in the combinations and relations described some of these may be altered and others omitted without interfering with the 115 more general results and effects outlined and the invention extends to such use.

What we claim is:—

1. Supervisory mechanism comprising, in combination, a valve, means comprising a rotary stem for operating said valve, a manually operable record-producing device, a member rotated by rotation of said stem, and means comprising a screw actuated by said member for controlling manual operation of said device.

2. Supervisory mechanism comprising, in combination, a valve, means comprising a rotary stem for operating said valve, a watchman's recording key, a member rotated by rotation of said stem, and means comprising a screw actuated by said member for controlling access to said key. 40
3. Supervisory mechanism comprising, in combination, a valve, means comprising a rotary stem for operating said valve, a manually operable record-producing device, a screw-threaded member spaced from said stem, means for rotating said member by rotation of said stem, and means controlled by said member for controlling manual operation of said device. 45
4. Supervisory mechanism comprising, in combination, a valve having a rotatable member for operating the same, a second rotatable member, means comprising an endless flexible element operatively connecting said members, a watchman's key movable from a position in which it is operable to produce a record to a position in which it is inoperable to produce a record, and means actuated by said second rotatable member for moving said key during only a portion of the total movement of said first named rotatable member. 50
5. Supervisory mechanism comprising, in combination, a valve having a rotatable stem for actuating the same, a casing surrounding said stem, a housing secured to said casing, a rotatable member within said housing, means for rotating said member by rotation of said stem, a rectilinearly slidable member within said housing and operatively associated with said rotatable member to be actuated thereby, a manually 55
- operable recording device, and means actuated by said slidable member for controlling manual operation of said device. 60
6. In combination, a valve having a rotatable stem, a rectilinearly movable element, means comprising a sprocket chain connecting said stem and element for simultaneous movement, a member mounted for movement about an axis and operable by and upon initial movement of said element in a predetermined direction and locked against movement on further movement of said element in the same direction, and a recording device controlled by said member. 65
7. In combination, a valve having a rotatable stem, a rectilinearly movable element, means comprising a sprocket chain connecting said stem and element for simultaneous movement, a rock shaft, a member mounted on said rock shaft and operable by and upon initial movement of said element in a predetermined direction and locked against movement on further movement of said element in the same direction, a manually operable recording device, and means secured to said rock shaft for controlling said device. 70
8. The combination set forth in claim 6 in which the recording device is a watchman's time clock key. 75
9. The combination set forth in claim 7 in which the recording device is a watchman's time clock key. 80

In testimony whereof we hereto affix our signatures.

ELLIS C. HEALY.
